UNITED STATES PATENT OFFICE.

GILBERT P. RITTER, OF CHICAGO, ILLINOIS, ASSIGNOR TO HARRY C. BUHOUUP, OF SAME PLACE.

DRAFT-RIGGING FOR RAILWAY-CARS.

SPECIFICATION forming part of Letters Patent No. 670,784, dated March 26, 1901.

Application filed December 22, 1900. Serial No. 40,767. (No model.)

To all whom it may concern:

Be it known that I, GILBERT P. RITTER, a citizen of the United States, residing at Chicago, in the county of Cook, State of Illinois, have invented certain new and useful Improvements in Draft-Rigging for Railway-Cars; and I hereby declare the following to be a full, clear, and exact description of the same, reference being had to the accompanying drawings, in which—

Figure 1 is a view from below, partly in horizontal section, of draft-rigging embodying my invention, the parts being in the normal condition or at rest. Fig. 2 is a view similar to Fig. 1, the parts being shown in the position they assume during draft. Fig. 3 is a view partly in vertical longitudinal section and partly in side elevation of the draft-rigging shown in Fig. 1 and embodying my invention.

Like symbols refer to like parts wherever they occur.

My invention relates to that class of spring-cushioned draft-rigging wherein are combined draft and buffing devices, and has for its object to overcome the backlash or jumping of the devices when reversed, thus preventing those sudden and severe blows and shocks which tend to the deterioration and destruction of both the draft devices and the car-body.

As is well understood by those familiar with railway practice, in all cases where the end-wise movement of the draw-bar in draft and buffing is cushioned by springs or like means intended to gradually assume the load and relieve the structure of shocks and blows the movement of the draw-bar in pulling or buffing increases or diminishes the distance between the cars—lengthens out or shortens the train—and such lost motion when suddenly taken up by the springs upon the reversal of the draw-bar results in violent shocks highly injurious to the structure.

In order to overcome the jumping of the draw-bar at such times as the movement thereof is reversed, I combine with the draw-bar a series of rollers and yieldingly-supported rocking plates or track-plates with which the rollers coact, said rollers being located on op-

posite sides of and preferably equidistant from the rocking center of the track-plate, whereby a constantly-increasing resistance is applied to the draw-bar from the time of its initial movement in either direction, and such a construction embodies one feature of my invention. Preferably the rollers are journaled on an endwise movable draw-bar, and the yieldingly-supported rocking plates or track-plates are spring-supported on both sides of the rocking center or axis of motion and mounted on the draft-timbers of the car-body, and such an arrangement of the combination above noted embodies a secondary feature of my invention. I also prefer that the rollers shall taper from the center to the journals and that the rocking plates or yielding track-plates shall be correspondingly grooved on tapers which shallow continuously from the center to the ends of the track-plate, whereby the resistance to the endwise movement of the draw-bar in either direction gradually increases from the center or axis of the rocking plate or track-plate in either direction according to the movement of the draw-bar, the force being neutralized or counterbalanced when the rocking plate and draw-bar are in their normal positions or at rest, and such a construction embodies a third feature of my invention.

There are other minor features of invention, all as will hereinafter more fully appear.

I will now proceed to describe my invention more fully, so that others skilled in the art to which it appertains may apply the same.

In the drawings, 1 indicates a suitable housing or casing for the draft and buffing mechanism embodying my invention and by means of which it may be secured to the usual draft-timbers A A by bolting or otherwise. In the present instance this casing or housing is shown as composed of two like sections a and b, separately bolted to the respective draft-timbers A A, each section having spring-pockets 2 2 placed at equal distances from the transverse center of the housing or equally distant from the seat 3 of the rocking plate or track-plate 4. If preferred, how-

ever, the two sections may be formed integral or with a central web which passes under the strap B of the draw-bar and connects the side sections a b.

5 4 4 indicate rocking plates or track-plates, each of which, where two are employed, may be provided at its center with a hemispherical projection or pivot projection 5, adapted to rest in the pivot-seat 3 of the housing, so 10 that the rocking plate may tilt to accommodate itself to the endwise movement of the draw-bar and the travel of the rollers.

Within the spring-pockets 2 2 of the casing are springs 6 6, which may be provided with 15 rocking caps 6^a 6^a where they bear on the opposite ends of the rocking plate or track-plate 4, and said springs are inserted under more or less compression, so as to neutralize each other when the rocking plates are at rest or 20 in a normal condition and yet at all times preserve the contact between the said track-plates and the rollers, so that the movement of the draw-bar in either direction will be resisted by a constant yielding force. The rollers, two or more of which may be employed— 25 preferably two—are so arranged that when the rocking plate or track-plate is at rest (see Fig. 1) the rollers will stand on opposite sides of and preferably equidistant from the rocking 30 center or axis of motion of the track-plate, so that on the movement of the draw-bar in either direction one roller or set of rollers will move away from and the other roller or set of rollers will move toward the rocking 35 center of the track-plate, and the springs or yielding supports of the rocking-plate will be alternately compressed and permitted to expand, so as to maintain a constantly-increasing 40 resistance to the draw-bar from its initial movement in either direction.

The track-faces of the rocking plates 4 4 may be plain, if plain rollers are employed, and in any event will conform to the rollers, but preferably are used in conjunction with 45 rollers which taper from the center to the ends, and consequently are provided with track-grooves 4^a 4^b of greatest depth and width at the center, where they unite, and tapering or gradually shallowing and narrowing 50 outward to the ends of the rocking plate, as indicated in Fig. 3 of the drawings.

7 7 indicate rollers which may be journaled on the shank of the draw-bar, the tail-strap B of the draw-bar C, or in other manner suitably supported so as to coact with the draw-bar and the rocking plates 4. These rollers are preferably in the form of truncated cones 55 united at their bases, or, in other words, taper from the center to the ends, which form, when taken in connection with a corresponding track in the face of the rocking plate, increases the bearing between the rollers and the plate and insures the centering and travel 60 of the rollers.

65 The construction and combination of the devices being of the general character hereinbefore pointed out their operation will be

as follows: On either the inward or outward movement of the draw-bar the leading roller will travel away from the center of the rocking plate or track-plate which will force the plate outward at the corresponding end, gradually compressing one spring or set of springs and increasing the resistance to the movement of the draw-bar, while the following 70 roller will move toward the center of the rocking plate or track-plate and the rocking plate by its inward movement at the rear and the gradual expansion of the corresponding spring will be maintained in constant contact 75 with the following roller, so that on the reversal of the draw-bar resistance will be immediately applied by the rear spring to the draw-bar through the rocking plate and the following roller, which has in turn become 80 the leading roller, and said resistance will gradually increase during the entire reverse movement of the draw-bar. The tendency of the springs and rocking plate or track-plate to reach an equilibrium or state of rest will 85 counteract vibration and assist in bringing the draw-bar to its normal position. It will be noted that a single yieldingly-supported rocking plate or track-plate coacting with a plurality of rollers and the draw-bar constitutes 90 the typical combination and may be so employed in combination with an opposed support for the travel of the rollers and the centering of the draw-bar, but the arrangement herein shown, wherein two opposed yieldingly-supported rocking plates are combined with a pair of interposed rollers and with the draw-bar, is in my opinion the preferable form of 95 construction.

Having thus described my invention, what 105 I claim, and desire to secure by Letters Patent, is—

1. In a draft-rigging for railway-cars, the combination with an endwise-movable draw-bar, of a yieldingly-supported rocking plate 110 or track-plate, and a plurality of rollers arranged on opposite sides of the rocking center of said track-plate, substantially as and for the purposes specified.

2. In a draft-rigging for railway-cars, the combination with an endwise-movable draw-bar, of a plurality of yieldingly-supported rocking plates or track-plates arranged on opposite sides of said draw-bar, and a plurality of interposed rollers arranged on opposite 120 sides of the rocking centers of said track-plates, substantially as and for the purposes specified.

3. In a draft-rigging for railway-cars, the combination with an endwise-movable draw-bar, of spring-supported rocking plates, and interposed rollers carried by the draw-bar, said rollers being arranged on opposite sides of the centers of motion of the rocking plates, substantially as and for the purposes specified.

4. In a draft-rigging for railway-cars, the combination with an endwise-movable draw-bar, of a yielding rocking plate having diverg-

ing taper grooves, and rollers which taper reversely from the center, substantially as and for the purposes specified.

5. In a draft-rigging for railway-cars, the combination with an endwise-movable draw-bar, of rollers, a pivotally-supported track-plate for the rollers and springs for yieldingly supporting the ends of the track-plate, substantially as and for the purposes specified.

10. 6. In a draft-rigging for railway-cars, the combination with an endwise-movable draw-bar, suitable rollers, and a pivoted track-

plate, of springs which yieldingly support the ends of the track-plates, and rock-caps interposed between the springs and track-plate, substantially as and for the purposes specified.

In testimony whereof I affix my signature, in presence of two witnesses, this 20th day of December, 1900.

GILBERT P. RITTER.
